UNITED STATES PATENT OFFICE.

EMIL HOKENSON, OF CHICAGO, ILLINOIS, ASSIGNOR OF ONE-HALF TO LARS LINDSKOG,
OF CHICAGO, ILLINOIS.

WINDOW-SCAFFOLD.

1,209,839.

Specification of Letters Patent. Patented Dec. 26, 1916.

Application filed January 15, 1915. Serial No. 2,341.

To all whom it may concern:

Be it known that I, EMIL HOKENSON, a citizen of the United States of America, and a resident of Chicago, county of Cook, and 5 State of Illinois, have invented certain new and useful Improvements in Window-Scaffolds, of which the following is a specification.

The main objects of this invention are to 10 provide an improved form of window scaffold adapted for temporary suspension at the windows of a building, so as to be conveniently used by window washers, painters and others who have occasion to work on or 15 about the windows; to provide improved supporting means adapted to be quickly and easily arranged for securing the window scaffold in place without necessitating the use of any fastenings which must be em- 20 bedded in the window frame or walls of the building; to provide improved means for adjusting the elevation of the platform with respect to the window ledge; and to 25 provide an improved arrangement of the supporting means on the platform whereby the scaffolding may be folded into compact form for storage and transportation.

An illustrative embodiment of this invention is shown in the accompanying drawings, in which:

Figure 1 is a perspective view of the improved scaffolding as arranged in position on a window ledge. Fig. 2 is a perspective view of the window scaffold folded ready 35 for transportation or storage. Fig. 3 is an enlarged detail of one of the brackets as viewed from the left of Fig. 1.

The embodiment of this invention comprises a platform mounted on a pair of supports which are adjustably carried on 40 brackets, arranged to rest upon the window ledge and to be retained in position by means of flexible connections attached thereto and to clips shaped to engage the inner edge of 45 the window sill. The supports and the platform are connected so as to be folded together into compact form whereby the scaffolding is conveniently carried about from place to place.

50 In the construction herein shown in the drawings, the platform 1 is in the form of a plank of suitable thickness to provide sufficient strength for supporting a workman.

The supports 2 are constructed of bars or members 6, 7, and 8, which are preferably 55 ordinary 2x4 timbers arranged in the form of right-angle triangles. The platform 1 rests on the bars 6 each of which forms one leg of the respective right-angles. The bars 7, forming the other legs of the right-angles, 60 extend downwardly adjacent to the building. The bars 8, forming the hypotenuses of the triangular supports, are either ex- 65 tended beyond the bars 7 to engage the wall of the building, or have plates 9 attached thereto which extend beyond the bars 7 and carry the rollers 10, so as to coat with the brackets in supporting the scaffolding in place.

The brackets 3 are preferably malleable 70 castings and are made to fit over the bars 7 and be adjustable along the same, so as to vary the elevation of the platform with respect to the window ledge. The brackets are locked in any desired position on the bars 75 7 by means of pawls 14 pivoted to the brackets 3, so as to engage the notches 15 formed in the bars 7 and exposed through opening 3,1, formed in said brackets. A gravity latch 16 is pivoted on each of the 80 brackets 3 and arranged to engage the respective pawls 14 so as to lock them in the notches 15.

The clips 5 are metal stampings made U-shaped in cross-section so as to conveniently 85 engage the inner edge of the window sill, thereby serving as an anchor for the chains 4.

The chains 4 extend through stirrups 17 formed on the inner ends of the brackets 3 90 and engage pins 18 extending horizontally outward from the opposite ends of the brackets 3. This arrangement of attaching the chains allows the scaffolding to be used on windows where the distance from the 95 ledge to the sill varies.

Hinges 19 connect the supports 2 to the platform 1, so that the supports may be folded up against the platform 1, whereby the scaffolding is conveniently carried from 100 place to place or may be stored away in a small space.

Although but one specific embodiment of this invention has been herein shown and described, it will be understood that numerous details of the construction shown

may be altered or omitted without departing from the spirit of this invention as defined by the following claims:

I claim:

5. 1. A window scaffold, comprising a platform and supports carrying said platform, said supports having horizontal parts arranged for engagement with a window ledge so as to normally rest thereupon and having other parts below normally arranged to bear upon the wall under the window ledge, said platform and horizontal parts being relatively adjustable whereby the elevation of said platform with respect to the window ledge may be altered.
10. 2. A window scaffold, comprising a platform, supports carrying said platform and having their lower ends arranged to bear against the wall adjacent to a window, and brackets carried by said supports and adapted to rest upon a horizontal part at one side of the window, said brackets and platform being relatively adjustable whereby the elevation of said platform with respect to the window ledge may be altered.
15. 3. A window scaffold, comprising a platform, a pair of supports carrying said platform and having their lower ends arranged to bear against the wall adjacent to a window, brackets slidably mounted on said supports and adapted to rest upon a horizontal part at one side of the window, a pair of clips adapted to engage a part at the opposite side of the window, and means connecting said clips and brackets, said brackets being adjustable along said supports so as to alter the elevation of said platform with respect to the window ledge.
20. 4. A window scaffold, comprising a platform, a pair of supports carrying said platform and having their lower ends arranged to bear against the wall adjacent to a window, brackets slidably mounted on said supports and adapted to rest upon a horizontal part at one side of the window, said supports having horizontal parts arranged for engagement with a window ledge so as to normally rest thereupon and having other parts below normally arranged to bear upon the wall under the window ledge, said platform and horizontal parts being relatively adjustable whereby the elevation of said platform with respect to the window ledge may be altered.
25. 5. A window scaffold, comprising a platform, a pair of supports carrying said platform and having their lower ends arranged to bear against the wall adjacent to a window, brackets slidably mounted on said supports and adapted to rest upon a horizontal part at one side of the window, said supports having horizontal parts arranged for engagement with a window ledge so as to normally rest thereupon and having other parts below normally arranged to bear upon the wall under the window ledge, said platform and horizontal parts being relatively adjustable whereby the elevation of said platform with respect to the window ledge may be altered.

part at one side of the window, said supports having notches formed therein, pawls on said brackets engaging said notches for locking said supports to said brackets, clips adapted to engage a part at the opposite side of the window, and means connecting said clips and brackets.

5. A window scaffold, comprising a platform, a pair of supports carrying said platform and having their lower ends arranged to bear against the wall adjacent to a window, brackets slidably mounted on said supports and adapted to rest upon a horizontal part at one side of the window, said supports having notches formed therein, pawls on said brackets engaging said notches for locking said supports to said brackets, a gravity latch on each of said brackets adapted to lock the respective pawls in said notches, clips adapted to engage a part at the opposite side of the window, and means connecting said clips and brackets.

6. A window scaffold, comprising a platform, a pair of supports carrying said platform and having their lower ends arranged to bear against the wall, adjacent to a window, brackets secured to said supports and adapted to rest upon a horizontal part at one side of the window, a pair of clips adapted to engage a part at the opposite side of the window, chains attached to said clips, stirrups formed on the inner ends of said brackets, and pins on the other ends of said brackets, said chains being adapted to pass through said stirrups and engage said pins so as to provide a rigid connection between said clips and brackets.

Signed at Chicago this 13th day of Jan., 1915.

EMIL HOKENSON.
